UNITED STATES PATENT OFFICE.

GUSTAF DE LAVAL AND ERNST ELIS FRIDOLF FAGERSTRÖM, OF STOCKHOLM, SWEDEN.

TURBINE.

986,472.

Specification of Letters Patent. Patented Mar. 14, 1911.

Application filed June 16, 1910. Serial No. 567,262.

To all whom it may concern:

Be it known that we, GUSTAF DE LAVAL, residing at 6 Torstensonsgatan, and ERNST ELIS FRIDOLF FAGERSTRÖM, residing at 1 5 Sigtunagatan, Stockholm, Sweden, subjects of Sweden, have invented new and useful Improvements in or Relating to Turbines, of which the following is a specification.

This invention relates to turbines of the 10 well-known de Laval type and provides an improved construction of such turbines and improved means whereby the direction of rotation can be reversed merely by the operation of a valve controlling the admission 15 of the actuating fluid.

It has heretofore been proposed to provide turbines with oppositely directed sets of vanes on each wheel, of which one set is operative while the main shaft is rotating in 20 one direction and the other set is operative while the main shaft is rotating in the other direction, and to provide each set of vanes with a correspondingly directed admission nozzle, a valve being provided to supply the 25 actuating pressure fluid through either nozzle to either set of vanes accordingly as the main shaft is required to rotate in one or the other direction. With such arrangements however it has been usual to employ a number 30 of vane wheels arranged on one shaft and contained either in a single casing or cylinder, or in separate casings or cylinders, and to pass the steam through these vane wheels successively, allowing the steam to 35 expand by degrees or in stages as it passes from one vane wheel to the other. This arrangement although it hypothetically utilizes to the best advantage the energy of the actuating fluid due to its pressure, results in 40 inefficient working due to losses arising from an incomplete utilization of the energy of the actuating fluid due to its velocity.

In carrying the present invention into practice, a turbine comprising a single vane 45 wheel having vanes of the kind used in impulse or in combined impulse and reaction turbines, is provided with two concentric sets of vanes respectively curved in opposite directions. In the casing or cylinder inclosing this wheel two annular chambers are 50 provided corresponding to the two sets of vanes and arranged co-axially and preferably laterally thereto. The actuating pressure-fluid is supplied to either of these chambers, at will, by a convenient form of multiple-way or like valve, and a convenient

number of nozzles spaced around each chamber, open from the interior of the chamber against the corresponding sets of vanes. Now, in such a turbine, in order to utilize 60 the kinetic energy of the actuating fluid to the best advantage, the vane wheel must revolve at a very high speed and, consequently, it is necessary, in many cases, to provide a suitable arrangement of speed reducing 65 gearing between the vane wheel shaft of the turbine and the machine or instrument driven thereby. For this purpose a small pinion or gear wheel is mounted on the main shaft and engages with a large gear 70 wheel mounted on an auxiliary shaft rotating in bearings provided therefor in the turbine casing so as to provide a self-contained turbine engine which can be coupled directly to an ordinary machine or instrument to be 75 driven thereby, such as, for example, a ship's propeller shaft, a crane or winding drum, a vehicle driving axle or the like.

Thus the present improved turbine comprises a single vane wheel having two sets 80 of vanes, two delivery nozzles or sets of nozzles arranged in combination with the vanes to form a reversing turbine, valve for supplying steam to one or other of the nozzles or sets of nozzles, at will, and an auxiliary 85 shaft mounted in bearings provided on the turbine casing and connected to the vane wheel shaft by speed reducing gearing. By this arrangement a reversing turbine is provided in which the vane wheel rotates at an 90 extremely high velocity to utilize, with the highest possible degree of efficiency, the energy of the actuating fluid due to its velocity, and which can nevertheless, as a self-contained engine, be coupled directly by reason of the provision of the auxiliary shaft and speed reducing gearing, to a propeller 95 shaft, winding drum or other like mechanism.

In the accompanying drawing which 100 shows how our said invention may be conveniently and advantageously carried into practice, Figure 1 shows a central longitudinal section of a turbine embodying the present improvements. Fig. 2 is a perspective 105 view of one of the double-vaned elements from which the vane-wheel is built up. Fig. 3 shows a longitudinal section of part of a turbine constructed with a modified arrangement of reversing valve. Fig. 4 is a 110 diagram illustrating a further modified form of reversing valve. Fig. 5 is a diagram

illustrating a modified construction of vane-wheel hereinafter referred to.

Referring to Fig. 1, *a* is the hub of a vane-wheel mounted on a shaft, *b*, and carrying at its periphery a number of double-vaned elements each comprising a pair of oppositely directed vanes *c*, *d* to form when built up on the wheel two concentric sets of oppositely curved vanes. Each double-vaned element may be conveniently made in the form or shape shown in Fig. 2. Steam or other actuating fluid is conducted to these vanes through passages or channels provided between concentric conical shells *e* with helical or inclined ribs *f* extending into the spaces between them as shown in Fig. 1, so as to form sets of nozzles *g*, *h*, which discharge the actuating fluid against the vanes in the required direction. The actuating fluid is supplied to these sets of nozzles alternatively from separate annular chambers *i*, *j*, to either of which the said actuating fluid is admitted from a supply pipe *k* by a valve *l*. This valve *l*, is provided with ports *m*, *n*, *o*, establishing communication between the supply pipe *k* and ports *p*, *q*, leading to the annular chambers *i*, *j*, respectively. The actuating fluid after passing through the vanes enters an exhaust chamber *r* through a port *s* from which it is led away by the exhaust pipe *t*. The vane-wheel shaft *b* has mounted thereon a pair of helical gear-wheels *u*, *u* engaging with corresponding helical gear-wheels *v*, *v* fast on an auxiliary shaft *w* mounted in suitable bearings provided in the turbine casing. This auxiliary shaft transmits the power developed by the engine to the machine to be driven, through a suitable coupling one member of which is indicated at *x*. In the position of the valve *l* shown in Fig. 1, the actuating fluid passes from the pipe *k* through the ports *n*, *o*, *q* into the chamber *j* from whence it is discharged through the nozzles *h* against the vanes *d* for rotation in one direction. The direction of rotation is reversed by turning the valve *l* so that the port *m* registers with the supply pipe *k* whereby the port *n* is brought into register with the port *p* and the actuating fluid is admitted to the annular chamber *i* and nozzles *g* by which it is discharged against the vanes *c*. By turning the valve *l* so that neither of the ports *m*, *n* registers with the supply pipe *k* the supply of actuating fluid is cut off from the engine entirely.

The double-vaned element shown in Fig. 2 comprises a shank portion *y* which is secured to the hub *a* by any usual or convenient means. The oppositely curved vanes *c*, *d* are bounded in a radial direction, and also separated from each other, by segmental portions *z* which in the completed wheel form continuous rims. This construction of vane-wheel is found to be very convenient

but it is not an essential part of the present invention as any other suitable construction of wheel with two oppositely directed sets of vanes, may be substituted therefor. For example as shown in Fig. 5, the hub *a* 70 may be provided with two sets of double-vaned elements *c*, *d* arranged on opposite sides of a stationary set of similar double-vaned elements *c'*, *d'* arranged on a suitable part of the engine casing. Each of these 75 double-vaned elements is similar to that shown in Fig. 2. The vanes *c* are however turned in the same direction while the vane *c'* is turned in the opposite direction, and the vanes *d*, *d'* are likewise turned in opposite directions. It is obvious that this 80 form of construction can be extended to comprise any number of rotary sets of vanes with interposed stationary sets of vanes.

The particular form of the nozzle *g*, *h* is 85 immaterial so long as the actuating fluid is discharged thereby in one direction against the vanes *c* and in the other direction against the vanes *d*, therefore, in lieu of the construction of nozzles shown in Fig. 1, 90 separate tubular nozzles of the well-known type may be provided leading from separate apertures in the walls of the chambers *i*, *j* and arranged to discharge the actuating fluid in opposite directions, respectively. 95

In the modified form of valve shown in Fig. 3, the actuating fluid is admitted from the supply pipe *k* through the ports *m*, *n* to the ports *p*, *q* respectively under the control of a valve *l'*. When this valve is in its 100 mid-position both the ports *p*, *q* are closed as will be readily understood by a consideration of this figure.

An alternative arrangement of valve shown in Fig. 4 comprises a slide valve *l''* which is shown in its mid-position closing both of the ports *p*, *q*. By moving this valve toward the left the port *p* is opened and by moving it toward the right the port *q* is opened. 110

In a turbine engine constructed as hereinabove set forth, the vane-wheel and its shaft rotate at an extremely high speed whereby the kinetic energy of the actuating fluid is utilized in the most efficient and 115 economical manner, while at the same time the direction of rotation can be readily and quickly reversed, and the engine works with substantially the same efficiency in either direction. Moreover, by the provision of the auxiliary shaft *w* and gearing *u*, *v*, within the casing of the engine itself, the latter can be employed to drive a propeller shaft, winding drum, vehicle axle, or the like without the employment of any detached gearing, resulting in an economy in the space occupied by the engine and a mechanism driven thereby, and in the labor and in the cost of coupling the engine to such driven mechanism. 120 125 130

Having now particularly described the nature of our invention and the manner of its operation, what we claim is:

1. A reversible steam-turbine, comprising, in combination, a single vane wheel with two sets of oppositely curved vanes, said vane wheel being mounted on a flexible shaft, distributing ports registering with one of said sets of vanes, distributing ports registering with the other of said sets of vanes, all of said distributing ports being positioned on one side of said vane wheel, a single valve controlling the admission of the driving medium to said distributing ports, an auxiliary shaft and a speed-reducing gearing connecting said auxiliary shaft to the vane-wheel shaft.

2. A reversible steam-turbine, comprising, in combination, a single vane wheel mounted

on a flexible shaft and carrying two sets of 20 vanes curved in one direction and two sets of vanes curved in the opposite direction, a series of guide vanes arranged on a suitable part of the engine casing between said rotating vanes, distributing ports on one side 25 of the vane wheel, a valve controlling said distributing ports, an auxiliary shaft and a speed-reducing gearing connecting said auxiliary shaft to the vane-wheel shaft.

In testimony whereof we have signed our 30 names to this specification in the presence of two subscribing witnesses.

GUSTAF DE LAVAL.

ERNST ELIS FRIDOLF FAGERSTRÖM.
